(57) CLAIM

I claim the ornamental design for a holder for beverage bottles and similar articles, as shown.

DESCRIPTION

My design relates to a holder for holding beverage bottles and similar articles of the type most often used to contain water or soft drinks. The beverage holder is designed to sit on a flat surface and be lifted by a single hand.

FIG. 1 is a perspective view of my design.

FIG. 2 is a bottom plan view thereof.

FIG. 3 is a top plan view thereof.

FIG. 4 is a front elevation view thereof; and,

FIG. 5 is a side elevation view thereof.
